Primary Examiner — George D. Kirschbaum*Assistant Examiner* — Lillian Windham(74) *Attorney, Agent, or Firm* — Muncy, Geissler, Olds & Lowe, P.C.(57) **CLAIM**

The ornamental design for a prism for measuring, as shown and described.

DESCRIPTION

FIG. 1 is a front side view of a prism for measuring showing our new design.

FIG. 2 is a rear side view thereof;

FIG. 3 is a top plan view thereof;

FIG. 4 is a bottom plan view thereof;

FIG. 5 is a right side view thereof, the left side view being a mirror image thereof;

FIG. 6 is a top, front, and left side perspective view thereof; and,

FIG. 7 is a bottom, rear, and right side perspective view thereof.

In the drawings, the broken lines depict portions of the prism for measuring that form no part of the claimed design.
